UNITED STATES PATENT OFFICE

GLENN E. EDMUNDS, OF COLUMBUS, OHIO

VALVE MECHANISM FOR INTERNAL COMBUSTION ENGINES

Application filed August 30, 1929. Serial No. 389,411.

This invention relates to improvements in valve mechanism for internal combustion engines, and has for its primary object the provision of a valve mechanism which is simple, positive and efficient in design and wherein an improved cam or eccentric mechanism is provided for effecting the operation of the individual valves, whereby the valves will be both opened and closed by the direct action of the cam or eccentric means with the end in view of obtaining the correct opening and closing motion of the valves at all engine speeds.

It is another object of the invention to provide a valve operating shaft which is mounted for rotation in connection with a pair of adjustable bearings, and wherein provision is made for raising and lowering said bearings for the purpose of simultaneously adjusting all of the individual valves operated by the shaft, whereby such adjustments may be quickly and accurately made as well as maintained "for long periods of operation."

For a further understanding of the invention reference is to be had to the following description and the accompanying drawings wherein:

Figure 1 is a view partly in vertical longitudinal section and partly in side elevation of an internal combustion engine provided with a valve mechanism comprising the present invention,

Figure 2 is a vertical transverse sectional view taken on the line 2—2 of Figure 1,

Figure 3 is an enlarged sectional view on the line 3—3 of Figure 1,

Figure 4 is a horizontal sectional view on the plane disclosed by the line 4—4 of Figure 3,

Figure 5 is a side elevation of the valve stem receiving portion of the cam yoke, and Figure 6 is a side elevation of the valve adapted for connection with the cam yoke.

Referring more particularly to the drawings, the numeral 1 designates the cylinder structure of an internal combustion engine, in which is formed the usual cylinders 2 for the reception of the sliding pistons 3. Arranged on the cylinder structure 1 is a removable head 4 in which is formed valve cham-

bers 5 which communicate with inlet and exhaust ports 6 and 7. The communication between these ports and the cylinders 2 is regulated, as usual, by a plurality of tappet valves 8 which are formed to include the usual heads 55 9 which engage with valve seats 10, the heads being provided with upwardly extending stems 11 which cooperate with the actuating mechanism hereinafter more fully described.

The upper portion of the head 4 is provided with threaded sockets 12 which receive vertically extending bearing screws 13, disposed at opposite ends of the cylinder block. The screws 13 are provided with intermediately disposed wrench receiving surfaces 14 and said screws on the opposite sides of the surfaces 14 are provided with right and left handed threads. The upper portions of the screws 13 are received within threaded openings provided in bearing blocks 15, which are provided with bushings 16 for the rotatable reception of the opposite ends of a valve operating shaft 17. One end of the shaft 17 is provided with a spiral gear which meshes with a worm 18 slidably keyed on an upright shaft 19 which is driven by the crank shaft (not shown) of the engine. It will be seen that by rotating the screws 13 the bearing blocks 15 and the shaft 17 may be adjusted bodily for the purpose of regulating the degree of clearance provided by the valves 8 when the latter are in open positions. The screws 13 are equipped with lock nuts 20 by which the desired adjustments of the operating shaft are maintained.

Formed with the shaft 17 in alignment with the tappet valves 8 are eccentrics or cams 21. In this instance the eccentrics have been illustrated, although it will be understood by those skilled in the art that cam surfaces may be used depending upon the stroke which is to be imparted to the valves. Therefore, for present purposes the terms, "eccentrics" and "cams" are to be used synonymously.

Surrounding the eccentrics 21 are yokes 22 which are provided with rollers 23 arranged for engagement with the peripheral surfaces of the eccentrics 21 and disposed on diametrically opposed side of said eccentrics.

This construction is such that the rotation of the eccentrics will impart back and forth reciprocatory motion to the yokes in a positive, self actuated or unaided manner. The lower portions of the yokes 22 are formed with sockets 24 in which are received studs 25 formed upon the upper ends of sleeves 26. Pins 27 pass through registering openings provided in the studs and in the lower portions of the yokes 22 to produce a rigid unitary assembly. The lower portions of the sleeves 26 are formed with annular flanges 28 which constitute seats for the reception of coil springs 29. The upper ends of these springs engage washers 30 loosely received upon the sleeves. By reference to Figures 3 and 4 it will be observed that the valve stems 11 are positioned within bores 31 provided in the sleeves 26, and that the upper ends of the stems 11 are formed with transverse openings for the reception of cotter keys 32. The ends of these keys are receivable within elongated slots 33 provided in the yoke extensions or sleeves 26.

It will be observed that as the operating shaft revolves, the eccentrics 21 thereof operate to impart timed back and forth motion to the yokes. This in turn effects at regulated intervals the desired opening of the valves 8 for the purpose of controlling the admission or exhaust of gases into and from the cylinders 2. This motion of the valves is positively effected in both opening and closing directions by the cam and eccentric mechanism, without relying upon springs, which renders the action positive at all engine speeds. When the valves are closed further upward movement of the yokes, in response to the action of the eccentric, merely serves to compress the springs 29 and to thus firmly seat the valve heads 9 in connection with the seats 10. It will be observed that the springs 29 are located above the engine head 4 and are therefore beyond the range of the destructive heat developed by the operation of the engine. For this reason the springs are capable of maintaining their effectiveness for long periods of use.

The valve mechanism may be enclosed by means of a housing 34, which may be held in place by means of screws 35 arising from the bearings 15 and secured by cap nuts 37. The top of the housing may also be provided with guide sockets 38 in which are received stems 39 projecting from the yokes 22. These stems serve to guide the movement of the yokes and also permit of their lubrication. Through the provision of the housing 34 and also due to the general construction of the valve operating mechanism the latter is extremely quiet in operation and is not likely to produce the operating noises so common in overhead valve motors. In this connection, while the invention has been disclosed as applied to an overhead valve motor, it is obvious that

its principles are likewise applicable to motors of other standard designs, such as the customary L or T head motors, Diesel engines and other types.

In view of the foregoing it will be seen that the present invention provides a simple yet highly efficient valve mechanism which is not likely to become out of order or to occasion constant adjustment and repair. The mechanism is particularly well adapted for the so-called "high speed" or "high compression" internal combustion engines of modern design, although the mechanism is, of course, applicable to other types of engines or pumps. While I have described what I consider to be the preferred form of my invention, nevertheless it will be understood that structural variations may be made therein without departing from the scope of the following claims.

What is claimed is:

1. In an internal combustion engine, a valve operating shaft, bearings arranged at the opposite ends of said shaft for effecting its support and rotation, and a pair of screws having opposed right and left hand threads engaged with said bearings and with a stationary base for adjusting said shaft and the valve operating mechanism carried thereby. 90
2. In an internal combustion engine, a valve operating shaft, bearings arranged at the opposite ends of said shaft for effecting its support and rotation, and a pair of screws having engagement with said bearings and with a stationary base of said engine for adjusting said shaft and the valve operating mechanism carried thereby. 95
3. In an internal combustion engine, a valve operating shaft, a pair of spaced bearings on said shaft for effecting its support and rotation, and means for raising or lowering said bearings in a true vertical plane with respect to a stationary part of said engine for effecting the adjustment of said shaft and the valve operating mechanism carried thereby. 105

In testimony whereof I affix my signature.

GLENN E. EDMUND.
